COUNTER

Allan Constantine, Warsaw, N. Y.

Application May 16, 1932, Serial No. 611,556

4 Claims. (Cl. 235—117)

This invention relates to golf stroke counters and has for its object to provide one of the golf clubs, preferably the putter which is used for the last stroke or strokes in placing the ball in the hole, with a stroke registering device in the handle thereof.

Another object of this invention is to make this stroke counting device simple and inexpensive in its manufacture.

10 Another object of this invention is to so embody the stroke counting device in the handle of the club that it will not in any way interfere with the use of the club.

Another object of this invention is to provide 15 the counter stroke device with a totalizer on which the total numbers of strokes may be registered.

Another object is to provide a device that will be in the hand of the player ready for use whenever he needs it.

All these and other objects of this invention will become more readily apparent from the detailed description which follows, reference being had to the accompanying drawings in which

25 Figure 1 is a longitudinal sectional view of the handle of a golf club with my counter stroke device embodied therein.

Figure 2 is a side elevation of the club handle with the counter stroke device with the number 30 of strokes for the first and second hole registered thereon.

Figure 3 is a transverse sectional view of the handle and counter stroke mechanism, the section being taken on the line 3x—3x of Figure 1.

35 Figure 4 is a cross section of the club handle and counter stroke mechanism, the section being taken on the line 4x—4x of Figure 1.

Figure 5 is a sectional view of a modified form of the counter wheel.

40 Figure 6 is an end elevation of another modified form of the counter wheel.

Figure 7 is a longitudinal sectional view of a handle with another modified form of the counter incorporated therein.

45 Figure 8 is a vertical sectional view of the handle and counter illustrated in Figure 7, the section being taken on the line 8x—8x of Figure 1.

Figure 9 is a detail view of the assembled 50 counter mechanism before it is inserted into the handle.

Figure 10 is a detail view of a modified locking mechanism for the operating member of the counter.

55 Figure 11 is a detail perspective view of a

sleeve carrying the numerals for the counter wheels which may be slipped over the counter wheels and suitably fastened thereto in place of having the numerals provided directly on the periphery of the counter wheels illustrated in Figures 7 and 8.

In the several figures of the drawings like reference numerals indicate like parts.

The stroke counting device forming the subject matter of my invention is incorporated in 10 the handle of the hollow shaft of the club which, for this purpose, is simply provided with a series of windows or sight openings thru which the numbers on the counter wheels of the registering mechanism can be observed. The device is operated by the end of the handle which in no way interferes with the ordinary use of the handle.

As illustrated in the figures, the handle section 1 forms a continuation of the shaft 2. The shaft and its handle section are made up of 20 metal tubing, although for the purpose of my invention, only the handle portion need be made tubular.

Within the tubular handle are provided and 25 suitably fastened the spacing washers 3 and 4, one near the inner end of the handle and the other at the outer end thereof. Between these washers are located the counter wheels 5 to 16 inclusive which space each other to locate their numbers in line with the windows or sight openings 17 provided in the handle. Nine of these openings are used for the counter wheels which register the number of strokes for each of the nine holes and these are marked 1 to 9 inclusive. Three additional openings near the end of the 30 handle and slightly spaced from the first nine holes cooperate with three counter wheels on which the total number of strokes at the end of the game are registered.

Each of the counter wheels comprises a pair 40 of sleeves 18 and 19 which are suitably fastened together with one sleeve telescoped over the other. The outer sleeve 18 has an annular flange or wall 20 formed at one end, and the inner sleeve 19 has an annular flange or wall 21 formed 45 at the other end so as to form bearings and spacing members which center and space the counter wheels on the counter operating member 22. From the periphery of the inner sleeve 19 are struck in the radially projecting longitudinal flanges 23, 23 which form suitably spaced shoulders within the counter wheels with which the counter wheels are rotated as will herein-after be described.

From the periphery of the outer sleeve 18 of 55

each counter wheel are struck out the friction members 24, 24 which are adapted to frictionally engage the inside of the handle to frictionally hold the counter wheels in the position into which they are moved by the counter operating member 22.

On the perimeter of each counter wheel are provided a series of numerals which are in line with the windows or sight openings 17 in the handle 1 so that on the rotation of a particular counter wheel a numeral, corresponding to the number of strokes taken for the hole to be registered by this counter wheel, is brought in register with the sight opening 17 of this hole in the handle 1.

Nine sight openings are provided in the handle and after nine holes are played the total number of strokes are registered on the "total" counter comprising the three smaller sight openings near the end of the handle and the counter wheels cooperating therewith. These latter counter wheels are provided with numerals 1, 2, 3, 4, 5, 6, 7, 8, 9 and 0 so as to indicate together if necessary a total of more than one hundred strokes. In playing on a golf course with eighteen holes, the number of strokes on the first nine holes is registered and their total transferred to the total counter. The number of strokes taken for the second nine holes is registered in the same way as the first nine holes and may be registered on the total indicated on the total counter for the first nine holes in order to indicate thereon the number of strokes taken for the eighteen holes.

The counter wheels are operated by the operating member 22 which comprises a tubing which carries on the inside at an intermediate point a cotter pin shaped spring 25. This spring is suitably anchored in the tubing and the sides thereof are bent out at opposite sides to provide the lugs 26 and 27 thereon. These lugs project thru suitable openings in the tubular operating member to have them engage between the shoulders 23 of the counter wheels and make contact therewith to rotate the counter wheels on the rotation of the operating member 22.

The tubular operating member is provided at its outer end with a short handle 28 which forms a continuation of the handle 1 of the shaft of the club. In the handle 28 of the operating member is anchored the spring pressed latch 29 which projects out of the handle into the end of the washer 4 and engages behind the shoulder 30 provided therein. The engagement of the spring pressed latch 29 behind the shoulder 30 thus normally or automatically locks the handle 28 of the operating member 22 to the handle 1. A thumb member 31 is carried by the spring pressed latch 29 in a suitable opening in the side of the handle 28 so that on the depression of this thumb member the spring pressed latch is disengaged from the shoulder 30 and the handle 28 with its operating member is free to be pulled away from the handle 1. In the closed position of the operating member 22 in which the handle 28 thereof is locked to the handle 1 of the shaft, the protruding lugs 26 and 27 of the cotter pin shaped spring 25 are located outside of the spacing washer 3 in an inoperative position in which the operating member cannot effect the setting of the counter wheels. When it is desired to operate one of the counter wheels, the handle 28 is unlocked as above described and the operating member pulled out of the handle 1 to a position in which the lugs 26 and 27 engage into the counter wheel which is to be operated thereby. For ex-

ample, if the number of strokes taken for the second hole is to be registered by the counter wheel cooperating with the sight opening marked 2 for the second hole, the operating member is pulled out of the handle as illustrated in Figure 2 until an annular line marked 2 is brought in register with the end of the handle 1. This line indicates that the operating member has been moved to a position in which the yielding lugs 26 and 27 engage into counter wheel 6. A rotation of the operating member 22 by its handle 28 in this position then brings the lugs 26 and 27 in engagement with shoulders 23 within this counter wheel which will rotate the counter wheel on the continued rotation of the operating member. The counter wheel is rotated until the desired numeral appears in the sight opening. The operating member is then pushed back into the handle. In this way any one of the counter wheels may thus be set by simply withdrawing the operating member to a position in which the corresponding calibration on the operating member is brought to the end of the handle 1. The operating member is then rotated within the counter wheel to bring it to the desired position and then returned.

The counter wheels registering the total number of strokes for either nine or eighteen holes played, are operated in the same manner as the counter wheels which register the number of strokes for each of the holes.

In Figure 5 I have illustrated a sectional view of a slightly modified form of one of the counter wheels in which a pair of friction springs 32 and 33 are supported on the inner sleeve to provide the frictional contact between the counter wheels and the inside of the handle.

In Figure 6 I have illustrated an end elevation of another modified form of the counter wheel in which the friction springs 34 and 35 are used to provide the friction between the counter wheels and the handle to keep the counter wheels from freely rotating within the handle.

Figures 1 to 6 of the drawings show the counter wheels longer than they need be in practice and it is understood that they may be made very much narrower in order to reduce the length of the group of counters and have them operate in a minimum space.

In Figures 7 to 9 inclusive I have illustrated a more simplified construction of the counter mechanism. In this form each of the counter wheels 40 comprises a sleeve with an annular inwardly projecting flange 41 at one end and the shoulders 42 struck in from the periphery thereof. These counter wheels are mounted in a sleeve 43 and are spaced in this sleeve between the washers 44 and 44A thereof. Struck in from the sleeve 43 are a series of spring fingers 46 which engage the periphery of the counter wheels to make frictional contact with them and yieldingly center these wheels within the sleeve. These spring fingers keep the counter wheels from freely rotating within the sleeve.

The sleeve 43 is cut away at a point below the sight openings in the handle 2 and in this cut away portion is placed a transparent strip of material 48 such as celluloid which permits the reading of the numbers thru the sight openings in the handle but keeps foreign matter from entering the counter mechanism. The sleeve with the counter mechanism is inserted into the handle 2 and is suitably anchored therein as for example by means of the screw 47.

In the form of the counter mechanism illus-

trated in Figure 7 the yielding lugs 26 and 27 of the cotter pin shaped spring 25 serves to hold the handle 45 of the operating member against the handle 2 of the club by their engagement behind the washer 44.

While I have described my counter as applied to golf clubs, it is understood that the same counter or a modification of it may be used for other registering purposes.

10 Of course the counter shown and described may be changed in various ways, and variations may be required under certain conditions, therefore, while some of the constructional details are deemed preferable and I have shown and described these specifically, it is to be understood that I do not limit myself to such precise construction but consider that I am at liberty to make such changes and alterations as fairly come within the scope of the appended claims.

20 In Figure 10 I have illustrated a modified form of locking means for locking the handle of the operating member to the handle of the club. This comprises a cotter pin shaped spring 50 which is suitably mounted in the operating member and carries the locking dogs 51 and 52 which are adapted to engage behind the locking flange provided in the washer 44A. The cotter pin shaped spring 50 is compressed to disengage the locking dogs 51 and 52 from the locking flange by means of the buttons 53 and 54 provided on the outer ends of the spring 50.

25 The numerals for the counter wheels may be etched or otherwise formed on a separate sleeve 55 and the sleeve telescoped over the counter wheel. Such a sleeve is illustrated in Figure 11.

30 I claim:

1. In a counter mechanism for golf club handles the combination of a hollow shaft and a hollow handle, concentric bearing means within the hollow handle, an operating member mounted to rotate and slide within said bearing means and extend from the outer end of the handle into the hollow shaft, a series of counter wheels mounted to rotate within said handle concentric 40 to said operating member and spaced therefrom, flanges separating consecutive counter wheels and encircling said operating member, an inwardly projecting member carried by each of said counter wheels and a spring pressed member 45 carried by said operating member and adapted to yield on the longitudinal movement of said operating member to consecutively and automatically engage behind each of said flanges on the endwise movement of said operating member in a 50 uniformly held radial position thereof and adapt-

ed to engage the inwardly projecting members of said counter wheels on the rotating movement of said operating member, said hollow handle having a sight opening for each of said counter wheels.

5 2. In a counter mechanism for golf club handles having a series of cylindrical counter wheels mounted to rotate therein the combination of an operating member mounted concentrically within said counter wheels and adapted to rotate and slide back and forth therein, said operating member having a pair of diametrically opposite openings therein, a spring located within said operating member so as to have part of said springs project thru the openings in said operating member and successively and automatically engage into said counter wheels during the endwise movement in a uniformly radial position of said operating member and engage said counter wheels during the rotating movement of said operating member.

10 3. In a counter mechanism for use in golf club handles the combination of a sleeve member, a series of tubular counter wheels mounted to rotate in said sleeve member and held conveniently spaced therein, a radial lug projecting inwardly from each of said counter wheels, a counter operating member mounted centrally of said sleeve member and adapted to rotate and move endwise therein, yielding counter operating 15 means carried by and cooperating with said counter operating member to permit the manual selection of any of said counter wheels and provide an automatic engagement of the selected 20 counter wheels by said counter operating means 25 while moving said counter operating member endwise in a uniformly radial position thru varying radial positions of said counter wheels.

30 4. In a counter mechanism for use in golf club 40 handles, a sleeve member, a series of cylindrical counter wheels mounted to rotate within said sleeve member, flanges separating consecutive counter wheels, an operating member mounted to slide endwise within said counter wheels, a 45 yielding member carried by said operating member and projecting from the periphery thereof, said member yielding inwardly of said operating member on its movement over the flanges between said counter wheels on the endwise movement of said operating member and automatically returning to engage the counter wheels between said flanges.

ALLAN CONSTANTINE. 55
